DAMPER AND HEATING UNIT

Benjamin S. Kagan, Rock Island, Ill., assignor to
American Machine and Metals, Inc., East
Moline, Ill., a corporation of Delaware

Application December 26, 1946, Serial No. 718,573

3 Claims. (Cl. 98—38)

1

The invention relates to the combination of a damper and heating unit permitting air to be passed through the heating unit or to be bypassed around the heating unit.

There are many applications in which air is passed through a unit placed at the entrance to a cabinet either to heat or to refrigerate the contents of the cabinet. The unit is generally held at the constant temperature. Since it is often necessary to control the temperature of the air passing through the cabinet part of the air is drawn through the heating unit and part around the heating unit to secure a temperature between that of the unit and the ambient temperature. At certain stages of the process it may even be necessary to pass all of the air around the heating unit so that only air at the ambient temperature is supplied to the material. The invention is illustrated by a particular application in which the air is heated although it will be understood that the same device could be used to refrigerate the air. When such a unit is applied to drying laundry, hot air is drawn through the heating unit to evaporate the moisture in the clothes. Dampers are usually provided to guide the incoming air to the coils to heat it or to bypass the coil.

The loading opening must be at work level; therefore, the damper and heater must be placed at the top of the dryer. That puts them above the head of the operator. The damper must be so designed that it can be moved by the operator who is standing in front of the machine and grasps the handle projecting to one side of the sliding damper without binding.

The object of the present invention is to provide a combined unit comprising a box containing heating coils partly filling an inlet opening and a damper sliding over the top of the box to optionally permit the flow of air through that part of the inlet opening covered by the box or through that portion of the inlet opening outside of the box.

A further object of the invention is to provide such a heating box in combination with two damper sections horizontally sliding toward or from each other in a manner to either prevent the flow of air around the heating box and compel it to flow to the heater or to prevent the flow of air through the heater and compel it to flow around the heater box.

A further object of the invention is to provide a sectional damper of the type indicated in which the movement of one section is automatically correlated to the movement of the other section.

2

A further object of the invention is to provide a damper having correlated sections which may be moved without binding by a handle placed outside of the track on which the damper moves.

5 A further object of the invention is to provide such a sectional damper which may be moved without binding by a handle placed both outside of the track and below its level.

Fig. 1 shows a perspective of a damper heater applied to a common form of dryer.

Fig. 2 is a plan view showing the damper sections and the heater as they appear in a top view of the cabinet shown in Fig. 1.

Fig. 3 is a vertical section drawn to an enlarged scale and taken through the damper and heater and the adjacent portions of the cabinet parallel to the front of the cabinet along line 3—3 in Fig. 2.

Fig. 4 also drawn to an enlarged scale is a vertical section through the damper and heater taken along line 4—4 in Fig. 2.

Fig. 5 is a fragmentary top view of one section of the damper together with the related portion of the cabinet drawn on enlarged scale.

25 Fig. 6 is an end view shown to an enlarged scale of one section of the damper taken along line 6—6 in Fig. 5.

In the drawings 1 indicates, generally, a heater of any desired type. 2 indicates, generally a sliding damper. 3 is one form of cabinet in connection with which the heater and damper may be advantageously employed. The cabinet 3 may have a door 4 suitable for loading the products to be dried into the cabinet. The air is admitted 35 to the cabinet through the large square opening 5 in the top of the cabinet and passes out through a duct 6 from the lower part of the cabinet. It is immaterial for the purposes of the invention whether the air flow is created by a suction device 40 connected with duct 6 or whether a blower within the cabinet draws the air in through opening 5 and discharges it through the duct 6.

The heater generally indicated at 1 consists of heating coils 7 supported in parallel walls 8. The 45 heating medium, which in the form here illustrated may be steam, enters through pipe 10 and passes out through pipe 11 after having passed through the coils 7. Two side walls 12 at right angles to the walls 8 cooperate to form a vertical 50 rectangular passage the upper end 14 of which is directly below the damper. When air is drawn in at the top through the space circumscribed by the walls 8 and 12 it passes over the heating coils, becomes heated and passes on through the cabinet 55 as hot air. The damper generally indicated at 2

3

consists of two sections 16, 17. Each of these sections consists of a sheet metal plate 18 having flanges 19 turned down along two opposite edges of the damper. The upper edge 20 of wall 12 extends above the bottom of the down-turned flanges 19. It will be clear by referring to Fig. 3 that when sections 16, 17 are in the positions shown air can enter through the top opening 5 into the cabinet 3 only through the heating coils. Accordingly, the cabinet is supplied entirely with hot air. When the two sections 16, 17 are slid toward each other until the flanges 19 of the two sections abut in the center of the cabinet, they will completely shut off any flow of air through the heating coil, the air now passing around the heater. The top of cabinet 3 extends over the sections 16, 17 to the edge 21 of the opening 5 in the top of the cabinet. This leaves spaces between the wall 12 and the edge 21 which permit air to be drawn into the cabinet when the damper has been moved to a position to close off the flow of air through the heater. Accordingly, it is evident that by sliding the damper into a suitable position the cabinet may either be supplied entirely with cold air which bypasses the heater or entirely with hot air which passes through the heater, or such intermediate mixtures of hot and cold air as may be determined by the position of the damper.

It is found convenient to keep the movement of the two sections in step by a device which will cause one damper to be moved automatically when the outer damper is moved. Such a device is shown by the endless belt 25. This belt passes over idlers 26 supported on the top of the cabinet 3.

The section 16 is attached to one side of the endless belt at 27 and the section 17 correspondingly on the other side of the belt at 28. A handle 29 is attached to one of the sections 16. Section 16 is moved by grasping the handle 29 and the other section will also be moved by the belt.

The cabinet shown in Fig. 3 is generally above the operator's eye level so that it becomes necessary to extend the handle out toward the front and downward below the plane of the sections 16, 17 as shown in Fig. 4. This may be accomplished by attaching a bar 24 to the section 16 and bending it outward and downward over the front of the cabinet as shown.

Referring to the top plan view, Fig. 2, it is obvious that as the handle 29 is moved to the right there will be a tendency to turn the section around a point in the vicinity of the attachment point 27. If the section 16 were directly supported at each end in a track 30 this would cause this section to bind.

Reference to Fig. 4 will show that as the operator grasps handle 29 the weight of his hand will also tend to bind the section 16 in a vertical plane. The pressure of his hand will tend to push the section 16 downward against the horizontal flange 31 of the track 30 at the end of the section nearest the handle and similarly will cause the far end of the section to bind against the underside of the top of the cabinet.

To avoid this binding two projecting portions 33 of section 16 carry rollers 34 free to revolve on vertical studs 35 carried by the extension 33. Two other extensions 36 project from the end of the section 16 and are turned down at right angles. These sections carry horizontal studs 37 on which rollers 38 turn. Reference to Fig. 5 will indicate that this arrangement of at least two rollers revolving about a vertical stud and

4

two rollers revolving about a horizontal stud at each end of section 16 will permit the section to be moved in tracks 30 without binding despite the fact that the handle 29 is placed far to one side of the center of the section and below the plane of the section.

In the operation of this device the heating fluid is passed through the coils 7 and air is drawn or forced out through the duct 6 passing in through the top opening 5. The door 4 is closed after the material to be dried has been placed in the cabinet 3. The handle 29 is placed so that the desired temperature is attained in the cabinet. Normally the handle will be moved to the extreme left in Fig. 2 at the start to give the maximum air temperature. The material, however, may require slow heating in which event the damper is moved to only partially open the flow of air through the heater 1 and to permit some air to flow through that part of opening 5 which is outside the heater box.

Very frequently at the conclusion of the drying period it is desired to pass cold air through the device. To accomplish this the handle 29 is moved toward the right in Fig. 2 and this causes the edges 19 of the opposed sections of the damper to abut preventing any flow of air through the heater and allowing the full capacity of the air moving device to be satisfied with cold air.

While the invention has been described as applied to a dryer in which moisture is to be evaporated, it will be obvious that the device will be equally suitable for use in refrigerating process in which the coils 7 carry a refrigerant and the dampers permit the flow of air over the refrigerator coils in one position and around the refrigerator coil box in their other positions.

What I claim is:

1. In a cabinet extending upward from the floor beyond the level of the operator's shoulder and having a rectangular air passage which extends up through the top of the cabinet and a non-binding damper-plate movable in a horizontal plane by means of a handle in front of the cabinet and below the level of the damper, in combination, a cabinet, a rectangular air passage in the cabinet extending through the top of the cabinet, horizontal ledges extending along two opposite sides of said passage, an additional ledge above each of said ledges and parallel thereto, a movable metal damper-plate extending across said passage, sections along opposite edges of said damper-plate turned downward into vertical planes proximate to the edges of said ledges, studs extending outward from said vertical sections into the spaces between said upper and lower ledges, rollers free to turn on said studs cooperating with said ledges to permit the damper-plate to slide freely in a horizontal plane, a bar attached to the damper and bent downward over the front of the cabinet, an operating handle attached to aid bar below the plane in which the plate moves.

2. In a cabinet extending upward from the floor beyond the level of the operator's shoulder and having a rectangular air passage which extends up through the top of the cabinet and a non-binding damper-plate movable in a horizontal plane by means of a handle in front of the cabinet and below the level of the damper, in combination, a cabinet, a rectangular air passage in the cabinet extending through the top of the cabinet, horizontal ledges extending along two opposite sides of said passage, an additional

ledge above each of said ledges and parallel thereto, a movable metal damper-plate extending across said passage and punched along its opposite edges to form tabs some of which extend in the plane of the damper-plate into the space between the two ledges while the remaining tabs are turned downward into vertical panes proximate to the edges of said ledges, studs extending normal to each tab, rollers turning freely mounted on each stud to permit the damper-plate to roll freely upon said ledges and to guide them against the sides of said passage to prevent binding, a bar attached to one of the damper-plates and bent downward over the front of the cabinet, an operating handle attached to said bar below the plane in which the plates move, wheels supported at opposite ends of the passage, an endless chain passing over said wheels, attachments between said chain and each plate so that movement of one plate by said handle will cause the remaining plate to move in cooperation to open or close said air passage.

3. In a cabinet extending upward from the floor beyond the level of the operator's shoulder and having a rectangular air passage which extends up through the top of the cabinet and a non-binding damper-plate movable in a horizontal plane by means of a handle in front of the cabinet and below the level of the damper, in combination, a cabinet, a rectangular air passage in the cabinet extending through the top of the cabinet, horizontal ledges extending along two opposite sides of said passage, an additional ledge above each of said ledges and parallel thereto, a pair of movable metal damper-plates extending across said passage each plate being punched along its opposite edges to form tabs some of which extend in the plane of the damper-plates into the space between the two ledges while the remaining tabs are turned downward into vertical

planes proximate to the edges of said ledges, studs extending normal to each tab, rollers turning freely mounted on each stud to permit the damper-plates to roll freely upon said ledges and to guide them against the sides of said passage to prevent binding, a bar attached to one of the damper-plates and bent downward over the front of the cabinet, an operating handle attached to said bar below the plane in which the plates move, wheels supported at opposite ends of the passage, an endless chain passing over said wheels, attachments between said chain and each plate so that movement of one plate by said handle will cause the remaining plate to move in cooperation to open or close said air passage.
